United States Patent Office

Des. 212,717
Patented Nov. 12, 1968

212,717

CAMERA

Thomas C. Mills, Wheaton, Ill., assignor to Camera Corporation of America (Canada) Ltd., Toronto, Ontario, Canada

Filed Jan. 23, 1968, Ser. No. 10,277

Term of patent 14 years

(Cl. D61—1)

FIG. 1

FIG. 2

FIG. 3

FIG. 4

FIG. 5

FIG. 6

FIG. 1 is a perspective view of a camera showing my new design;

FIG. 2 is a top plan view thereof;

FIG. 3 is a front view thereof;

FIG. 4 is a right side view thereof;

FIG. 5 is a left side view thereof; and

FIG. 6 is a rear view thereof.

The bottom is plain and has the same outline as the top.

The carrying strap has been partially omitted from FIGS. 2, 3, 4 and 6 for convenience in illustration.

I claim:

The ornamental design for a camera, substantially as shown and described.
